UNITED STATES PATENT OFFICE.

LEXEY B. ELLIS, JR., OF MEMPHIS, TENNESSEE.

TOY.

1,323,033.

Specification of Letters Patent. Patented Nov. 25, 1919.

Application filed February 1, 1918. Serial No. 214,925.

To all whom it may concern:

Be it known that I, LEXEY BARRY ELLIS, Jr., a citizen of the United States, residing at Memphis, in the county of Shelby and State 5 of Tennessee, have invented certain new and useful Improvements in Toys; and I do hereby declare the following to be a full, clear, and exact description of the invention, such as will enable others skilled in the 10 art to which it appertains to make and use the same.

My invention relates to toys, and has for an object to provide a toy particularly adapted for the amusement of small children, 15 the toy being so constructed and arranged that it can be readily operated.

Another object of the invention is to provide a toy which consists of relatively movable members having figures associated 20 therewith whereby the operation of the members will result in the operation and movement of the figures, causing the figures to coöperate in their movements to produce an amusing result.

25 A further object of this invention is to provide a toy of this character, which will be simple, practical and comparatively inexpensive in construction and one that can be manufactured and sold at a low cost.

30 With these and other objects in view, the invention consists in the novel combination and arrangement of parts hereinafter more fully described and set forth in the claim hereto appended.

35 In the drawing:

Figure 1 is a front elevation of the device showing the same dotted in one position with the figures tilted.

Fig. 2 is a top plan view of the same.

40 Fig. 3 is an end elevation.

Like numerals of reference designate corresponding parts in all the figures of the drawing.

Referring to the drawing, the numerals 5 45 and 6 designate operating members, respectively. Each operating member has pivotally secured thereto a supporting block 7. The supporting block 7 is pivoted as at 8 to the operating members 5 and 6, respectively, 50 intermediate the ends thereof. A figure 9

is secured to the upper side of the block 7 and is located above the upper operating member 5.

A figure 10, representing a sailor, has its feet pivotally secured as at 11 to the operating member 6 adjacent one end thereof. The figure 10 is also pivotally secured as at 12 to one end of the operating member 5. The arms of the figure are extended and have secured thereto the representation of 60 a hammer or mallet designated 13.

A second figure 14 representing a soldier has its portion representing the feet pivotally secured to one end of the member 6 as at 15 and to the end remote from the end 65 carrying figure 10. The figure 14 is also secured as at 16 to the operating member 5 adjacent its free end so as to permit the portion in rear thereof to constitute an operating handle. Figure 14 has its arms extended in the direction of the other figure 70 and has secured thereto a mallet or hammer 17, the purpose of which will be hereinafter more fully described.

It will be understood from the foregoing 75 description taken in connection with the accompanying drawing that by virtue of pivoting figure 10 to the extreme end of the member 5 and to the member 6 adjacent its end it forms an operating handle, and by 80 pivoting figure 14 to the other end of the member 6 and adjacent the other end of the member that there is also provided another operating handle. By grasping the 85 two operating handles of the members 5 and 6, respectively, and moving them in opposite directions the hammer of one of the figures will be urged into engagement with one side of the head of the figure 9 due to the fact that the block and head are tilted by the 90 movement of the members 5 and 6 respectively.

Having thus described my invention what I claim is:

A toy comprising a pair of spaced parallel elongated operating members, a central figure pivoted to said operating members intermediate their ends, figures pivoted to said operating members on opposite sides of said central figure and representing a soldier and 100

a sailor, and mallets carried by the soldier and sailor and adapted for striking the head of the central figure upon the reciprocatory movement of said operating members, one end portion of each operating member being extended beyond the adjacent figure for providing operating handles.

In testimony whereof I affix my signature in presence of two witnesses.

LEXEY B. ELLIS, JR.
